Specification for Design.

Patented Jan. 10, 1922.

Application filed May 28, 1921. Serial No. 473,398. Term of patent 3½ years.

To all whom it may concern:

Be it known that we, ADA W. SCHEPPACH, IDA E. HUTTON, and ELIZABETH REEKS, all citizens of the United States, the first and third residing in Newark, in the county of Essex and State of New Jersey, and the second in Morristown, in the county of Morris and State of New Jersey, have invented a new, original, and ornamental Design for a Badge, Emblem, Pin, or Similar Article, of which the following is a specifi-

cation, reference being had to the accompanying drawing, forming part thereof.

The figure is a front elevation of a badge showing our design.

We claim:

The ornamental design for a badge, emblem, pin, or similar article as shown.

ADA W. SCHEPPACH.
IDA E. HUTTON.
ELIZABETH REEKS.
